UNITED STATES PATENT OFFICE

WILLIAM KNAPP, OF HOLLIS, NEW YORK

CEILING ELECTRIC-LIGHT FIXTURE

Application filed March 14, 1929. Serial No. 346,865.

This invention relates to improvements in electric fixtures and more particularly to that type of electric fixture adapted to fasten directly against a ceiling.

5 One object of the invention is to produce a fixture of the nature referred to of a simple and rigid construction.

Another object of the invention is to provide a cooling and ventilating system in a fixture of this character that will prevent the deterioration of the insulation of the current carrying wires in the ceiling, due to the heat generated by the lamps in such fixtures, and thus minimize the fire hazard.

15 A further object of the invention is to provide a fixture of this nature that will prevent any dust or dirt from the ceiling from falling into the globe or bowl attached thereto.

Another object is to produce a device of 20 the character described in which the maximum simplicity of construction and operation is secured.

Other objects and advantages will appear as the nature of the improvements is better 25 understood, the invention consisting substantially in the novel arrangement and co-relation of parts herein fully described, and illustrated in the accompanying drawings, wherein similar reference characters are used to describe corresponding parts throughout the 30 several views, and then finally pointed out and specifically defined and indicated in the appended claims.

The disclosure made the basis of exemplifying the present inventive concept suggests 35 a practical embodiment thereof, but the invention is not to be restricted to the exact details of this disclosure, and the latter, therefore, is to be understood from an illustrative, 40 rather than a restrictive standpoint.

The inventive idea involved is capable of receiving a variety of mechanical expressions, one of which, for the purpose of illustration, is shown in the accompanying drawings, in 45 which

Figure 1 is a side view partly in section of my improved electric fixture secured in place against a ceiling.

Figure 2 is a top plan view of the fixture and 50 Figure 3 is a bottom plan view thereof.

The electric ceiling fixtures now commonly used consist of a shell open at the top and bottom thereof in which a plurality of electric lights are supported and enclosed by a bowl or globe. These lights when lit generate a great amount of heat, which due to the construction of the fixtures has no means of escape and rises into the ceiling drying out the rubber covering or insulation of the current carrying wires in the said ceiling, causing the said insulation to crumble and fall off the wires. Should the wires cross at any point where the insulation has fallen off a short circuit and often a fire will ensue. Likewise due to the fact that the fixture is open at the top a great deal of dust and dirt from the ceiling, which is also open directly above the said fixture will fall into the bowl.

It is to eliminate these disadvantages and defects that I have perfected my present invention.

Referring now to the drawings in detail, 5 indicates the body portion of my improved fixture which is preferably made or spun of thin sheet metal, and consists of an upper cylindrical portion 6 and a lower reduced portion 7. A metal bracing or reinforcing disk or plate 8 at the bottom of the portion 6 separates and completely closes off the lower portion 7 from the upper portion 6. The said disk 8 is supported on an annular flange 9 and fits into a bead 10 on the portion 6, the said bead being spun when the disk is in position on the flange. A short distance above the disk 8 there is provided a second disk 12 made of any suitable heat and fire repelling material, such as for instance asbestos or the like. The said asbestos disk is supported between projections 13 and 14 punched out and bent inwardly from the outer circumferential wall 15 of the upper portion 6. Openings 16 and 17, the objects of which will presently be described, are formed by the punching and bending operation above mentioned.

The fixture is supported on a pipe 20 in the ceiling 21 and held against same by means of a hickey 22 threaded at one end to the said pipe 20 and at its opposite end to a short nipple 23 which passes through the disks 8 and 12 and is provided at the lower end 100

thereof with a lock nut 24. Sockets 25 and 26 are secured to the lower side of the disk 8 and are adapted to receive electric light bulbs 27 and 28. Lead wires 29 and 30 extend from the sockets 25 and 26 and pass through openings 31 and 32 in the asbestos disk 12 into and through a ceiling box 33 and are spliced or otherwise secured to the main current carrying wires 34 and 35 in the ceiling. These wires 34 and 35 are usually provided with a rubber insulation 36. A globe or bowl 37 closes the fixture at the bottom thereof.

Any heat generated by the lamps 27 and 28 when they are lit will be unable to pass into the ceiling through the asbestos disk 12 to affect the insulation of the wires 34 and 35, but the said heat will pass out through the openings 16. Cool air will also be permitted to pass into the fixtures through the said openings 16 as well as through the openings 17 thus providing a combined cooling and ventilating system. I have found in actual practice that this cooling and ventilating system is so effective, that it provides a lower temperature at the immediate vicinity of the lamps than at other parts of the ceiling.

From the foregoing it will be seen that I have provided an electric ceiling fixture having a cooling and ventilating system therein to prevent the insulation of the main current carrying wires from becoming deteriorated and peeling off the said wires, and to prevent the resultant short circuits and fires.

Having described my invention what I claim as new and desire to secure by Letters Patent is:

1. In an electric light ceiling fixture, a shell having an upper and lower row of perforations in the outer wall thereof, a heat insulating closure located between the said rows of perforations, and an electric light support below the heat insulating closure and perforations.

2. In an electric light ceiling fixture, a shell having an upper and lower row of perforations in the outer wall thereof, inwardly extending projections extending from the bottom of the upper row of projections and the top of the other row of projections, a heat insulating closure supported between the said projections and an electric light supporting member below the lower row of perforations.

3. In an electric light ceiling fixture, a body, an electric light supporting member therein, a heat insulating closure in the body above the light supporting member and a cooling and ventilating system comprising openings in the body above and below the closure.

4. In testimony whereof I hereunto affix my signature.

WILLIAM KNAPP.
